CLAIM

The ornamental design for a rocking chair, as shown and described.

DESCRIPTION

FIG. 1 is a front perspective view of a rocking chair, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The thin broken lines in the drawings illustrate the portions of the rocking chair, which form no part of the claimed design.

The thick broken lines representing stitching in FIGS. 2 and 8 are not part of the claimed design.
